UNITED STATES PATENT OFFICE.

LEVI SCOTT McMICKIN, OF COLD SPRINGS, TEXAS.

WIRE-STRETCHER.

SPECIFICATION forming part of Letters Patent No. 323,947, dated August 11, 1885,

Application filed May 25, 1885. (No model.)

To all whom it may concern:

Be it known that I, LEVI S. McMICKIN, a citizen of the United States, residing at Cold Springs, in the county of San Jacinto and 5 State of Texas, have invented a new and useful Improvement in Wire-Stretchers, of which the following is a specification, reference being had to the accompanying drawings.

My improvement relates to an improvement 10 in wire-stretchers; and it consists in the peculiar construction and arrangement of devices, as will be more fully set forth hereinafter.

In the accompanying drawings, Figure 1 represents a perspective view of my improved 15 wire-stretcher. Fig. 2 shows the stretcher in use. A represents a bar, which may be formed of wood or metal, and which is of suitable length. At one end of this bar is made a V-shaped notch, B, which is adapted to catch and 20 retain the barbed wire while the latter is being stretched.

As is herein shown, the bar is constructed of 25 wood, and is provided with metallic plates C on its notched end, which plates serve to prevent wear on the wood. The opposite extremity of the bar has a ferrule, D, which has a short arm, E, and a long arm, F, extending from 30 opposite sides, as shown. At the outer end of the arm F is a stud, G, which is serrated on its inner side, and in between the arms E and F is pivoted a cam-lever, H, which is provided with serrations on its edge facing the serrated stud. This cam lever H, in connection with the serrated stud, is adapted for clamping a smooth 35 wire and holding the same while being

stretched while building the fence. The wire to be stretched is first permanently secured at one end to one of the fence-posts, and the bar is then used as a lever for stretching the wire, each succeeding fence-post serving in turn as 40 a fulcrum therefor, as will be very readily understood.

I am aware that it has been heretofore proposed to notch the end of a wire stretcher bar so as to adapt it to catch and retain barbed wire while being stretched, and this construction broadly I disclaim. I am also aware that it has been heretofore proposed to provide a lever for stretching wire with a cam-dog for clamping the wire, and this also broadly I disclaim. 50

Having thus described my invention, I claim—

The wire-stretcher consisting of the bar notched at one end to receive a barbed wire, and provided with a ferrule at its opposite end, 55 having the short arm E and the long arm F, the stud G, serrated on its inner side at the outer end of the arm F, and the serrated cam-lever H, pivoted between the arms, the bar being adapted to be used as a lever in connection 60 with a fence-post as a fulcrum, substantially as described.

In testimony that I claim the foregoing as my own I have hereto affixed my signature in presence of two witnesses.

LEVI SCOTT McMICKIN.
